UNITED STATES PATENT OFFICE.

WILLIAM D. RUNDLETT, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

QUADRANT MECHANISM FOR MULES.

No. 866,307.

Specification of Letters Patent.

Patented Sept. 17, 1907.

Application filed August 17, 1905. Serial No. 274,540.

To all whom it may concern:

Be it known that I, WILLIAM D. RUNDLETT, a citizen of the United States, residing at North Andover, in the county of Essex and State of Massachusetts, have invented an Improvement in Quadrant Mechanism for Mules, of which the following description, in connection with the accompanying drawing, is a specification, like letters on the drawings representing like parts.

This invention in mules relates more especially to what is known as the quadrant mechanism.

The quadrant is that device having a screw that is turned by mechanism deriving its movement from an endless band deriving its movement from the carriage. The screw is provided with a quadrant-nut having a sheave over which passes the quadrant or winding chain connected with the spindle-driving drum, the movement of the screw being more or less according to the difference in diameter between the largest and smallest part of the cop on which the yarn is wound, and if there is a discrepancy in the operation of the feeding mechanism, due to strain on the nut exerted in spinning that will turn the quadrant screw, the screw when this is discovered must be turned by hand to secure the proper winding. In the class of quadrant mechanism where a friction has been used, the friction exerted constantly has to be overcome by the operative at the completion of the winding of a set of bobbins at which time and between the outward and inward run of the carriage preparatory to doffing, the quadrant screw must be turned backwardly to wind the quadrant nut down to its starting position toward the axis or the center of motion of the quadrant. This movement, provided the friction is set up to a point where it is safe to operate the mule, has to be done quickly and requires the exercise of considerable power on the part of the operative.

Figure 1 in side elevation and section shows a sufficient portion of a mule embodying my improvements to enable my invention to be understood; Fig. 2 a detail showing the quadrant screw and nut and some of the usual devices for turning said screw; Fig. 3 shows enlarged the quadrant arm, screw and nut, and my improvements added thereto; Fig. 4 is a left-hand side elevation of the parts shown in Fig. 3; Fig. 5 is a section on the line x, Fig. 3; Fig. 6 shows the band wheel and its ratchet wheel detached from the carriage and enlarged, and Fig. 7 is a section of Fig. 6 on the line x'.

Referring to the drawings, A represents part of the carriage having spindles A'; A² the spindle driving drum; B the shaft of the tension faller; B' a connected arm; C the shaft of the winding faller; C' a connected arm; O² a flexible connection suspended from said arms and extended about a sheave a of a leg a' movable

vertically in a guide a² of the carriage. A spring a³ acts 55 normally to depress said leg when the arm B' of the tension faller shaft is turned downwardly during the winding, the tension faller being then depressed by the strain of the thread running thereover.

D represents the quadrant arm; D' the quadrant 60 screw; D² its nut, D³ its sheave; d, d' bevel gears; d² a shaft having a pinion, d³; d⁴ an intermediate pinion engaging a smaller pinion d⁵ on a shaft d⁶, having a belt wheel d⁷ pivoted on a stud sustained by the stand employed for supporting the quadrant. A suitable 65 casting d¹⁰ on the floor is provided with a stud to sustain a grooved wheel d¹², and a casting d¹³ attached to the carriage sustains a wheel d¹⁴, and said casting has a stud d¹⁵. The wheels d⁷ and d¹² receive an endless belt d⁸ that between said wheels is passed partially 70 about the wheel d¹⁴, and also about a grooved wheel d¹⁶ on the stud d¹⁵.

The sheave D³ of the quadrant nut is surrounded by a chain D¹⁰ connected at one end to the stand D⁹ fixed to the floor, and at its opposite end with the usual 75 winding drum of the mule carriage from which the spindles derive their movement during winding.

The parts so far referred to are old and need not be herein further described with the exception that I have employed the wheel d¹⁰ to sustain a loose ratchet plate 80 d¹⁷, whereas in the old forms of construction the wheel d¹⁶ had a fixed ratchet plate.

Referring to the quadrant, I have fixed to the quadrant screw D' at the outer end of the quadrant arm D a plate or disk 10, and immediately above said disk I 85 provide the quadrant screw with a loose disk 12 represented as provided with a series of notches to leave teeth or projections 13. Above this disk I mount a friction plate 14 that is connected with the screw by a spline 15, see Fig. 5, so that said plate is free to move 90 longitudinally thereover, and bearing on the outer face of the plate 14 I have provided a spring 16, the force of which against said plate is controlled and made more or less by a nut 17 applied to the outer end of the screw D'. Between the fast plate or disk 10 and 95 the notched plate 12, I preferably provide a friction washer 18 of suitable material, preferably leatheroid or equivalent friction material, and I also provide a like washer 19 between the notched plate 12 and the friction plate 14.

By turning the nut 17 the pressure of the spring 16 against the plate 14 which is connected with the screw by the spline, may be made more or less so that said plate may be made to exert any degree of friction desired to prevent any rotation of the quadrant screw 105 due to strain on the quadrant nut, and by turning the nut not only the pressure of the spring may be varied and made more or less, but any wear of the fric-

tion plates may be compensated, so that the absolute control of the screw is obtained through the devices referred to. When it is necessary to revolve the quadrant screw backwardly to place the quadrant nut next 5 to the center of motion of the quadrant arm, it is only necessary to release the locking device 20 pivoted at 21, and acted upon normally by a pin 22 and spring 23, to keep the engaging part of said locking device in one of the notches of the plate. When this locking 10 device is pulled outward from its position Figs. 3 and 5, the mule operative may engage the handle 24 applied to the square upper end of the quadrant screw above the arm D, and may quickly and easily turn the quadrant screw backwardly to place the quadrant 15 nut in its starting position, and during this operation all parts of the friction device turn freely with the screw D'.

I believe that I am the first to employ with a quadrant screw any friction means in which the screw may 20 be turned, and a locking device to retard rotation of said screw as same is being turned during the regular operation of the mule, the disengagement of said locking device making inoperative the friction on the screw that the latter may be freely turned, and therefore I 25 do not desire to limit my invention to the exact construction of friction means shown but intend to cover any equivalently operating device.

Heretofore the quadrant screw D' in mules has been rotated by gearing operated by what is designated a 30 feeding means including the band d⁸, which band should be moved to actuate the quadrant screw just before the carriage completes its inward run toward the feed rolls, and just before the tension faller descends, and before the winding faller is raised to lock the tension faller in the position that it should occupy during 35 the next outward run of the carriage. When the wheel d¹⁶ is provided, as has been customary, with a fixed ratchet plate it frequently happens that the teeth of said plate are engaged by the leg a', due to 40 the depression of the tension faller at the rolls, and when the position of the fallers is being changed preparatory to the carriage being run out, but to insure the proper position of the quadrant nut the screw should be turned if necessary near the end of each 45 inward run of the carriage, and the screw should be turned before completing the inward run and before the change of position of the fallers. To provide against moving the screw and nut after or while the fallers are being changed at the rolls, and to insure 50 that said nut and screw be changed only at the proper time, that is, as the carriage is running in and before the fallers are changed, I have connected the ratchet plate d¹⁷ loosely with the wheel d¹⁶, by a pin e¹⁰ extended from said wheel into a slot e¹² of the ratchet 55 plate. The pin e¹⁰ is connected by a spring e¹³ with a stud e¹⁴ carried by the plate d¹⁷ and this plate has a limited amount of lost motion due to the slot e¹² and pin e¹⁰.

By mounting the ratchet plate loosely, as described, 60 on the wheel d¹⁶ should the leg drop momentarily during the changing of the fallers at the rolls, the plate may be turned during the final movement of the carriage and not turn the wheel d¹⁶ to move the band d⁸ and thus turn the screw and slide the nut thereon. In

my invention the nut is moved automatically only as 65 the tightness of the yarn requires. Therefore, mounting the ratchet plate loosely alongside of the wheel d¹⁶ avoids any accidental movement of the quadrant screw and its nut at the inward run of the carriage when the fallers are changing their position, and while 70 the tension faller is moving into its locked position at the rolls.

It will be understood from the foregoing description that the leg a' is not intended to engage the ratchet plate during the time that the position of the fallers 75 is being changed at the rolls, but if, in the operation of winding, the yarn should be too tight the leg may drop at any point in the inward run of the carriage, meeting the ratchet wheel, and turning the grooved wheel, thus moving the band d⁸ of the feed mechanism 80 to turn the quadrant screw and move its nut to relieve the tension on the yarn, this being done before changing the position of the fallers.

Having described my invention what I claim as new and desire to secure by Letters Patent is:—

85

1. In a mule, the combination with the quadrant, its screw, and means for operating it, of friction means, and locking means for said friction means, whereby when said locking means is in its operative position the screw may be turned in the friction means, and when the locking means is disengaged from said friction means the latter is rendered inoperative.

90

2. In a mule, the combination with the quadrant, its screw, and means for operating it, of friction means, and locking means for said friction means, whereby when said locking means is in its operative position the screw may be turned in the friction means, and when the locking means is in its inoperative position the screw and friction means may be turned in unison, and means to regulate the amount of friction to be overcome before the screw can be turned 100 in the friction means.

95

3. In a mule, the combination with the quadrant arm and its quadrant screw, of a plate fixed to said screw at the upper end thereof and above said arm friction devices surrounding said screw and co-acting with said plate.

105

4. In a mule, the combination with the quadrant screw and friction means including two plates mounted thereon and turning therewith, and an intermediate plate surrounding said screw loosely, of means to restrain the rotation of said intermediate plate, and means to vary the 110 extent of pressure of said plates on said intermediate plate.

110

5. In a mule, a quadrant arm, its screw, a plate fixed to said screw, and a friction-plate surrounding said screw loosely at one side said fixed plate, combined with a spring, and means acting thereon to control the friction of said 115 friction plate on said fixed plate.

115

6. In a mule, a carriage, winding and tension fallers mounted thereon, a leg controlled by said fallers, a quadrant, its screw, and means for turning said screw, including a band, of a wheel mounted on the carriage and having a ratchet plate applied to said wheel that it may have a limited amount of lost motion relative thereto, said ratchet being engaged to start the wheel in advance of starting said wheel during the inward run of the carriage and before changing the position of the fallers.

125

7. A quadrant arm, a quadrant screw, a friction device mounted on said screw, and a locking device sustained by said arm, the locking device when engaging said friction device preventing its rotation with said screw and when disengaged from said friction device permitting the latter 130 device to revolve with the screw.

130

In testimony whereof, I have signed my name to this specification, in the presence of two subscribing witnesses.
